(57) **CLAIM**

The ornamental design for a moisture sensor and controller, as shown and described.

DESCRIPTION

FIG. 1 is a front perspective view of a moisture sensor and controller;

FIG. 2 is a rear perspective view thereof;

FIG. 3 is a front elevation view thereof;

FIG. 4 is a rear elevation view thereof;

FIG. 5 is a top plan view thereof; and,

FIG. 6 is a right side view thereof.

Those portions of the Figures shown in dashed lines are for illustrative purposes only and form no part of the claimed design.
